ACCOUNTING MACHINE CONTROL MEANS

Walter A. Anderson, Fairfield, Conn., assignor to
Underwood Corporation, New York, N. Y., a corporation of Delaware

Application December 23, 1949, Serial No. 134,624

3 Claims. (Cl. 235—60.5)

1

The present invention relates to accounting machines having a traveling paper carriage and constructed and arranged to compute in a plurality of columns on a work sheet. This invention is specifically concerned with improved means for automatically controlling the various functions of an accounting machine as the carriage thereof is tabulated to its various columnar positions. A general type of machine to which the present invention is applicable is described in detail in O. J. Sundstrand Patents Nos. 1,946,505 and 2,088,982. The copending application No. 134,622, filed December 23, 1949 by O. W. Swanson, shows certain improvements over the structure shown in these Sundstrand patents.

A common form of work which machines of the type with which the present invention is concerned are called upon to perform is the listing in one column of folio numbers or other identifying indicia, listing amounts such as purchase prices in a second column and the listing of the amount of tax in a third column. The entering of the amounts and an automatic tabulation to the next columnar position is accomplished, as is well known, by a cycling of the machine instituted by depression of a motor bar. Immediately after beginning its tabulating movement after the entry of the amount in the third column, a control device on the carriage strikes a lever which causes an automatic carriage return to the first column position. Likewise when the carriage is in the third column position a control device on the carriage actuates a lever which causes a latch to be released so that during the entry cycle in the third column the roller platen will be line spaced automatically, as fully explained in the Sundstrand Patent No. 2,088,982 referred to above.

When listing the type of items referred to above, it frequently happens that there will occur a number of consecutive amounts upon which no tax is charged, in which case it will be appreciated that tabulation to the third column position is undesirable. It will be obvious that the description of the type of work to be performed, as noted above, is purely by way of example. As is well known, machines of this type may be provided with automatic controls for a wide variety of accounting set-ups. Thus the machine may be conditioned for adding in one register in the first column, for adding in another register in the second column and for adding in both registers in the third column. Likewise the machine may be conditioned for subtracting in any of the col-

umns desired. The present invention is only concerned with the provision of means for cutting out the third column when desired, that is, to return the carriage directly from the second column position without the necessity for tabulating to the third column.

Provision has previously been made of a key located upon the keyboard which when depressed will cause a power carriage return from any position. However, in order to enter the second column amount into the register of the machine, the motor bar must be operated and with the automatic controls arranged for listing in three columns, operation of the motor bar in the second column will cause the carriage to tabulate to the third column position. If no item is to be entered in the third column, the operator must either depress the motor bar in this third column position or depress the special carriage return key in order to get the carriage back in position for beginning the next line.

It is an object of the present invention to provide improved means whereby, in a machine of the type referred to above, the carriage may be automatically returned to the first column after the entry of the amount in the second column, without the necessity of tabulating to the third column or of depressing a special key, in cases where no entry is to be made in the third column.

It is a further object of the present invention to provide a control device which moves with the carriage and which while normally effective to select a register in a certain columnar position, may be readily adjusted to cause an additional function in that columnar position, such as the function of automatic carriage return and/or line spacing.

These and further objects, features and advantages will become readily apparent as the description of a preferred embodiment of the invention proceeds.

Referring now to the drawings:

Fig. 1 is a plan view of the device in position upon a machine and showing the various automatic controls which are operated thereby.

Fig. 2 is a side elevation of a portion of the automatic controls.

Fig. 3 is a perspective view of the device of the present invention, and,

Fig. 4 shows an example of the type of work which the present invention is designed to facilitate.

In Fig. 1 is shown a bracket 10 which is one of several fixed to the frame of the machine in

a manner not shown and of no importance insofar as the present invention is concerned. Stationarily mounted upon the bracket 10 and upon the other brackets not shown, is plate 11, only part of which is shown. A pivot post 12 is secured in the plate 11 in any suitable manner, and swivably mounted upon the post 12 are a plurality of function control elements 13, 14, 15 and 16, which control the functions of "subtraction," "non-add," "selection of B register" and "paper feed" respectively in a manner in which the present invention is not concerned but which is described in the copending application of O. W. Swanson, referred to above. The element or bail 16 is the only one with which the present invention is at all concerned; the mode of operation or the particular functions controlled by elements 13, 14 and 15 form no part of this invention and are merely indicated by way of example.

A control carriage is arranged to move in tabulating and return directions across the machine and this carriage is provided with a plate 17. The manner of mounting the plate 17 of course forms no part of this invention, it being sufficient for a complete understanding of the invention to point out that in its tabulating movement the plate 17 progresses from right to left as viewed in Fig. 1.

The plate 17 is provided with a series of notches 18 along one edge and with a series of openings 19. A large number of automatic control devices or column units may be mounted upon the plate 17 for controlling the function of the machine in its various columnar positions. When working with a form of the type shown in Fig. 4, it will be understood that three column units will be provided. Two of these units or devices are shown in Fig. 1 at 20 and 21. Each of the devices 20 and 21 is in the form of a generally U-shaped member having an attaching flange 22. The flange 22 of the unit 20 is provided with a downwardly extending ear 23 for cooperating with any desired one of the notches 18 and with an elongated slot 24 through which extends a screw 25 for holding said unit in position upon the plate 17.

The U-shaped portions of the column units are positioned with the open end of the U facing the plate 17, as best seen in Fig. 3. A series of slots 26 are milled through the closed end of the U. In the present showing, there are four slots 26 in each unit but it is to be understood that in some instances there may be many more. There is a slot 26 in each control device corresponding to each of the control elements 13-16.

From an inspection of Fig. 2 it is apparent that the slots 26 are cut deep enough to allow a cammed end 27, provided upon each of the control elements 13-16, to pass through as the column unit moves under said control elements. The control elements normally rest upon a rod 28 and only perform their controlling function when they are raised from the Fig. 2 position.

For causing the control devices to operate one or more of the elements 13-16, a means is provided for blocking the slot 26 corresponding to the particular element which is to be affected. This blocking means is merely a block-like member 29, reduced in section at its lower end and fitted into the slot 26 with its reduced end extending between the downwardly extending arms of the U, as best seen in Fig. 2.

Machines of the type with which this invention is useful are provided with tabulator stops so that the carriage will come to rest in proper

position for printing in the various columns of the work form being employed. The above described column units of course perform their controlling functions while the carriage is resting in its various columnar positions. The particular tabulator stop shown for purposes of the present description is indicated in Fig. 1 at 30 with a secondary or temporary stop being shown at 31. The particular construction and mode of operation of the tabulator stops of course form no part of this invention but the particular ones shown are fully described in my prior Patent No. 2,330,660 wherein the parts 30 and 31 correspond to the present parts 30 and 31 respectively. The tabulator stop 30 is normally in position to stop the tabulating movement by cooperation with the ear 23 of the column unit 20 or with a corresponding part of the unit 21 to be later described. During tabulation the stop 30 is momentarily lowered to allow the ear 23 to pass by and is then raised to a position to coat with the corresponding part of the next column unit.

At 32 is indicated a lever which when moved toward the left will institute an automatic carriage return to the first column position. The particular type of carriage return employed is of no consequence to this invention but the lever 32 shown herein may conveniently correspond to the lever 36 of Patent No. 1,901,135 issued March 14, 1933, to O. J. Sundstrand.

As previously pointed out, it is common to provide means for instituting a paper feed operation when the carriage is automatically returned to the first column position. The particular manner of performing this operation is not a part of this invention, but in Fig. 1 at 33 has been indicated a slide corresponding to the slide 1102 of the Sundstrand Patent No. 2,088,982, hereinabove referred to. The slide 33 moves toward the end of bail 16 during each cycle of the machine but as long as the bail is in its normal position, said slide cannot be given sufficient movement to cause a paper feeding operation.

The column unit 20 is the one employed in the first column when using a form such as shown in Fig. 4 and it will be noted that the blocking means 29 is in the slot 26 corresponding to the "non-add" control element 14 so that the numbers listed in the first column, which may be folio numbers or other identifying indicia, will not be added into any of the registers. It will be noted that the ear 23 extends far enough to coat with the tabulator stops 30 and 31 but does not extend far enough to strike the automatic return lever 32. Hence, when the machine is cycled to print the number in the first column, a tabulation is instituted, as is well known, and the carriage moves to the left until the column unit 21 strikes the tab stop 30. During this tabulating movement the ear 23 of column unit 20 passes by the lever 32 without striking it.

The basic column unit 21 is quite similar to the unit 20. As best seen in Fig. 3, the unit 21 comprises a generally U-shaped portion having slots 26 milled therethrough similarly to the unit 20. The basic unit 21 has an attaching flange 22 provided with a bent down ear 35 for fitting into one of the notches 18 in the plate 17 and is provided with an elongated slot 36 through which extends a screw 37 for securing said unit firmly to the plate 17. A slot blocking means 29 in this instance is provided in the slot corresponding to the control lever 15 so that B register will be selected in this column and the amounts printed on the form under the heading "value"

will be entered into the B register during the cycle.

In addition to the ear 35, the attaching flange is provided with a second ear 38, shown in dotted lines in Fig. 1. Mounted upon the unit 21 for sliding movement between two positions is a slide 39. The slide 39 is provided with an enlarged opening 40 for fitting loosely about the head of the screw 37 and with a pair of flanges 41 for embracing the ears 35 and 38 of the flange 22. A screw 42 extends through an elongated opening 43 in the slide 39 and is secured in the flange 22. A spring element 44 has an opening therethrough embracing the shank of the screw 42 and is held in place by the head of the screw. The spring 44 is provided with a projection 45 for cooperating with either of a pair of spaced dimples 46 provided in the slide 39.

The slide 39 is provided with a finger piece in the form of an upstanding flange 47 so that it may be conveniently moved between the full line and the dotted line positions shown in Fig. 1. The projection 45 on the spring element 44, by cooperating with one or the other of the dimples 46 serves to resiliently detent the slide in either of its positions.

A member 48 is provided with a positioning tab 49 fitted within a notch 50 provided in the slide 39 and is secured to said slide by means of a screw 51. The member 48 has a portion 52 fitted loosely about the U-shaped portion of the unit 21.

In instances where amounts are to be printed in all three columns of the form, the slide 39 is positioned as shown in full lines in Fig. 1. In this position, as the carriage tabulates to the second column, which in the example given is the column controlled by the unit 21, the left hand flange 41 of the slide 39 strikes against the tabulator stop 30 to thereby bring the carriage to rest in the proper position. The blocking means 29 selects the B register as stated above. After the entering and printing cycle the carriage tabulates to the third column position where it is again arrested by a column unit, not shown. It will be apparent that as the carriage is tabulated, the flange 41 will pass by the automatic return lever 32 without affecting same when the slide 39 is in its full line position.

When it becomes apparent to the operator that there will be a series of entries to be made not requiring the use of the third column, the "tax" column in the example illustrated, the slide 39 is merely moved from the full line position shown in Fig. 1 to the dotted line position. With the slide in the dotted line position, the machine still performs its usual function in the second column because the block 29 continues to select the B register, this being unaffected by the position of slide 39. However the slot 28 corresponding to the control element 16 is now blocked by the portion 52 of the slide so that instead of the control element 16 merely passing through the slot said element is raised. This raising of the element 16, removes its blocking end from the path of the slide 33 so that during the entry cycle, the slide 33 will be free to move its full extent and thereby cause a paper feeding operation as above pointed out.

Likewise, in the dotted line position of the slide 39, the flange 41 moves to a position for cooperating with the automatic return lever 32. Thus, as the carriage escapes, instead of completely tabulating to the third column position, the flange 41 contacts the lever 32 thereby causing the carriage

to automatically return to the first column position.

Without the slide 39, or with the slide 39 in its full line position, the carriage escapes to the third column position after the entry of the amount in the second column in the same manner as described with respect to tabulating from the first to the second column.

The right hand column unit, in the example illustrated the unit for the third column, not shown, is provided with a flange similar to the flange 23 of the column unit 20 but long enough to operate the lever 32 as the carriage begins to tabulate out of that column and thereby cause the carriage to return to the first column position.

Thus it will be seen that the present invention, while exceedingly simple, effects a considerable saving of time and wear by allowing the machine to which it is attached to be conveniently used for operating in a large number of columns or in a lesser number of columns.

Having hereinabove described my invention, I claim:

1. In an accounting machine having a traveling carriage and constructed and arranged to print and compute in a plurality of columns on a work sheet, a plurality of elements for controlling various functions of the machine, a member for instituting an automatic carriage return operation and a member for normally preventing an automatic line spacing operation but which may be moved to a position for allowing an automatic line spacing operation, a control device movable with the traveling carriage and provided with means for operating at least one of said elements, a slide carried by said control device, means for detenting said slide in a plurality of positions on said device, and means carried by said slide for operating the member for instituting an automatic carriage return operation and for moving the member for normally preventing an automatic line spacing operation when said slide is in one of its detented positions without interfering with the normal functions of said control device.

2. In an accounting machine having a traveling carriage and constructed and arranged to print and compute in a plurality of columns on a work sheet, a plurality of elements for controlling various functions of the machine, a member for instituting an automatic carriage return operation and a member for normally preventing an automatic line spacing operation but which may be moved to a position for allowing an automatic line spacing operation, a plurality of control devices movable with the traveling carriage, means provided upon one of said control devices for operating the member for instituting an automatic carriage return operation and for moving the member for normally preventing an automatic line spacing operation, and a slide carried by another of said control devices and movable to two positions in one of which positions it is effective to operate the member for instituting an automatic carriage return operation and for moving the member for normally preventing an automatic line spacing operation and in the other of which positions it is ineffective.

3. A control device adapted to be attached to a traveling carriage of an accounting machine, said device comprising a first element having a generally U-shaped portion, a plurality of slots extending transversely through said U-shaped portion, a second element slidably mounted upon

said first element, means on said second element embracing the U-shaped portion of said first element, a finger piece on said second element whereby said second element may be moved relative to said first element between a position wherein the means on said second element blocks one of said slots and a position wherein said means does not block any of said slots, and means for detenting said second element in each of its relative positions.
